UNITED STATES PATENT OFFICE

2,479,801

FIRE EXTINGUISHER

Fred A. Woodworth, Minneapolis, Minn.

Application June 24, 1946, Serial No. 678,910

5 Claims. (Cl. 169—2)

1

This invention relates to fire extinguishers.

Some of the structure of the present invention is an improvement over the invention disclosed in my co-pending application Serial Number 480,800, filed March 24, 1943, now Patent No. 2,402,704, and entitled "Fire control apparatus."

One of the objects of the invention is to provide a fire extinguisher which can be readily refilled with a common type of extinguishing fluid such as CCl_4 .

Another object of the invention is to provide an extinguisher including a casing adapted to hold a frangible container, the casing having an opening therein whereby a striker can be released to pass through said opening and break said container, and whereby the casing is provided with a flexible wire cloth liner which prevents the broken glass or other frangible material from escaping from the casing.

Another object of the invention is to provide a spring pressed plunger for fracturing the frangible container and means whereby said spring pressed plunger can be reset.

A further object of the invention is to provide an easily operable and highly efficient closure for the casing which holds the glass or other container for extinguishing fluid.

Still a further object of the invention is to provide a simple and effective alarm means which is operated when the spring pressed striker or plunger is released by the melting of a fusible link which normally anchors said spring pressed striker.

The above and other objects and advantages of the invention will more fully appear from the following description made in connection with the accompanying drawings, wherein like reference characters refer to the same parts throughout the views, and, in which:

Figure 1 is a view partially in side elevation and partially broken away showing the embodiment of the invention;

Figure 2 is a fragmentary view partially in section of the casing closure securing means;

Figure 3 is a fragmentary plan view of the structure in Figure 2;

Figure 4 is a plan view with part of the extinguisher fluid receiver broken away and with the casing closure removed;

Figure 5 is an enlarged fragmentary longitudinal vertical sectional view through a portion of the mechanism; and

Figure 6 is a vertical sectional view through the alarm unit shown in Figure 1.

The device includes a casing 10 which prefer-

ably is of metal which, as shown in Figure 5, is provided with a lower side wall opening or aperture 11. It should further be noted in Figure 5 that the bottom of the aperture 11 is located a short distance above the bottom of the casing 10.

Within the casing 10 is a cylindrical lining 12 which may conveniently be formed from wire cloth such as used for screening windows. It should be noted that the wire cloth 12 completely covers the opening 11 in the lower side wall portion of the container. Received within the wire liner 12 is a glass or other frangible container 13 which may be filled with CCl_4 or other suitable material for extinguishing fires.

The top of the casing 10 is provided with a removable cover 14. Extending upwardly from opposite points of the side wall of the container 12 are ears 15 having apertures 16 therethrough. A rod 17 is received in the apertures 16 and one end thereof is provided with a spring catch element 18 which is adapted to engage its adjacent ear 15 to releasably hold the rod 17 in position. This closure is provided to prevent the glass jar 13 from jostling from the casing 10 since it is contemplated that my apparatus is adaptable for use in moving vehicles. Means for securing the closure is readily receivable so that the user of the apparatus can easily recharge the device after it has been used.

Extending outwardly from the bottom of the casing 10 and in communication with the opening 11 in said casing is a pair of side frame members 19 and 20. Secured to the side frame member 19 is a mounting bracket 21 and a bracket 22 is suitably connected to the casing 10. The side frame members 19 and 20 are connected at their left hand ends by a U-shaped cross member 23.

Mounted between and supported by the side frame members 19 and 20 and communicating with the opening 11 in the wall of the container 10 is a receiver or chamber 24 having a downwardly extending sump 25 which is provided with a plurality of outlets 26. Extending into the receiver 24 is a rod 27 whose inner end is provided with a point 28. A helical spring 29 is positioned between the inner left end wall of the receiver 24 and the pointed head or end 28 on the plunger rod 27. The left hand or rear end of the rod 27 is provided with a flange 30 to which is secured a pair of spaced arms 31 having a bolt 32 connected between them. A U bolt 33 is shown mounted through the U-shaped cross piece 23 connecting the left hand ends of the frame members 19 and 20 and a fusible link 34 connects the

U bolt 33 with the straight bolt 32 mounted between the arms 31. Thus when the link 34 melts the spring 29 will move the plunger 27, 28 to the right with considerable force and the pointed end of the plunger will either penetrate the wire screen 12 or merely push it in and at the same time break the glass jar 13. Thereupon the extinguisher fluid will flow into the chamber 24 and thence to the sump 25 where it will spray from the opening 26, the apparatus normally being mounted at a relatively high point in the enclosure in which it is used. The wire prevents broken glass from escaping from the apparatus since even fine particles may at times cause damage or injury. This is particularly true where the closed receiver 24 is not used as is sometimes the case.

A threaded rod 35 is normally supported, as shown in Figure 4, by a pair of brackets 36 which are mounted on the casing side frame member 20. When the spring 29 has been released, it is necessary to reset the plunger. That is the function of the rod 35. As shown in Figures 1 and 5, the rod 35 is passed through a suitable aperture in the end member 23 which connects the frame members 19 and 20, and said rod 35 is threaded into a threaded aperture in the flange 30 on the plunger rod 27. A nut 36 on the rod 35 can be screwed up against the cross member 23 to gradually force the plunger to the left against the pressure of the spring 29. This reset unit is provided since in some cases the strength of the spring 29 is considerable.

In Figure 1 there is shown an alarm unit which can be used with the apparatus. It includes a panel 37 upon which is mounted a U-shaped bracket 38 having a lower arm 39 and an upper arm 40. The lower arm 39 is provided with a central aperture 41 through which a pair of spring mounted pins 42 extend, said pins being supported in a block of insulation 43 mounted on the under side of the arm 39. A spring actuated plunger 44 passes through a guide bracket 45 mounted on the arm 40 of the bracket 38, and said plunger 44 slidably extends through the arm 40 as well as the guide 45. A coil spring 46 lies between the under side of the arm 40 and an insulated head 47 on the end of said rod 44. A strip of metal 48 is mounted on the under side of the block 47 so that when the plunger 44 is moved downwardly the two spring supported pins 42 will be bridged by the metal. The plunger 44 is connected by a flexible cord or wire 49 to the pin 32 connecting the members 31 on the left hand end of the main plunger rod 27, as shown in Figures 1, 4 and 5. Consequently, when the fusible link 34 melts and releases the main plunger the cable 49 will also release the plunger 44 to bridge the contact pins 42, thereby energizing an electric alarm bell 50 shown in Figure 1. At the same time a pair of mechanically operated bells 51 will be operated by reason of linkage 52 which connects said bells to the head of the plunger 44, as clearly shown in Figure 1.

From the foregoing description it will be seen that I have provided a relatively simply constructed and operated fire extinguishing device which has several advantages. It is of a type which utilizes a frangible container, which can be readily replaced, and the replacement can be cheaply and easily filled with an extinguishing fluid. When the glass or other container is broken by action of the main spring pressed plunger the wire lining in the casing which holds

the glass container prevents the glass from escaping. As an added precaution against the escape of glass the opening 11 in the side of the casing 10 is located a short distance above the bottom of the casing so that tiny glass particles will not wash out of the casing with the extinguisher fluid but will be trapped in the bottom of the casing. The casing is provided with a simple and quickly operated closure and retainer therefor.

I have provided a simple and easily operated reset device and the alarm system which may or may not be used depending upon the location of the particular installation is simple and effective.

It will, of course, be understood that various changes may be made in the form, details, arrangement and proportions of the various parts without departing from the scope of my invention.

20 What I claim is:

1. In a fire extinguisher, a casing having an opening therein, a perforate element in said casing and covering said opening, a frangible container for fire extinguishing fluid in said casing, 25 said perforate element lying between the inner wall portion of said casing and said container, a striker supported adjacent said casing and movable through said opening, and said perforate element lying in the path of movement of said 30 striker and yieldable to permit said striker to break said container.

2. The structure in claim 1 and said perforate element being thin and flexible and non-brittle.

3. The structure in claim 1 and said perforate 35 element being a removable liner of wire cloth loosely received in said casing and readily removable therefrom.

4. In a fire extinguisher, a frangible container, 40 a spring pressed plunger mounted adjacent said container and releasable to strike the container, a reset rod detachably securable to said plunger, an abutment member through which said rod passes to engage said plunger, a nut threaded on said rod and movable against said abutment member to move said rod and said plunger against the action of the plunger spring.

5. In a fire extinguisher, a casing having a side wall with an opening therein, said casing having a closed bottom, said side wall opening being located a short distance above said bottom to provide a drop in the lower portion of the casing, a frangible container in said casing, a striker located adjacent said casing and movable through said opening to contact and break said container, 55 and a perforate element extending across said opening.

FRED A. WOODWORTH.
